INTERNAL GAS BURNER AND REMOVABLE LINER MEMBERS

Ernest G. de Coriolis and William Lehrer, Toledo,
Ohio, assignors to Surface Combustion Corporation,
Toledo, Ohio, a corporation of Ohio

Application April 26, 1947, Serial No. 744,130

2 Claims. (Cl. 158—99)

1

The present invention relates to an elongate gas burner for producing a line of flame and has for its object to provide an improved assembly of parts to the end that the burner may be well adapted to withstand relatively high temperatures without damage and be relatively simple to manufacture and withal be well adapted for its intended purpose, which is for use in connection with the heating of a continuously moving line of material as, for example, metal in strip form. For a consideration of what we believe to be novel and our invention, attention is directed to the following specification and the claims appended thereto.

In the accompanying drawing,

Fig. 1 is an isometric view of certain parts of the improved burner, the view being on an enlarged scale as compared with Fig. 2, which is a transverse sectional view of the burner. Figs. 3 and 4 are elevational views of separate end elements of the burner. Fig. 5 is an enlarged fragmentary sectional view on line 5—5 of Fig. 7. Fig. 6 is a partial side elevation and sectional view of the improved burner with an intermediate portion omitted. Fig. 7 is a fragmentary sectional view of parts shown in Fig. 2 except for a modified form of combustion space 32. Fig. 8 is a diagrammatic view showing the improved burners arranged in upper and lower groups to fire towards both the top and bottom sides of a line of strip metal 1 supported on a bed of rollers 2 and moving into and through a heat treating furnace 10.

The improved burner comprises a plurality of ceramic backing blocks 13 adapted to be arranged in two laterally spaced and longitudinally extending rows to form between themselves a longitudinally extending channel for a purpose presently appearing. Referring to Fig. 2, the right-hand blocks 13 are indicated by 14 and left-hand blocks by 15. The blocks are each adapted to be disposed against a flat wall member 24 of a longitudinally extending support generally indicated by 16 and to be held thereagainst by U-bolts 17 each adapted to be received in a side recess 18 of the block and to extend through said member. Short side walls 20 depend from said wall member 24 to form a guide way between which said backing blocks are mounted.

There is positioned in the channel between the two rows of backing blocks 13 two laterally spaced and longitudinally extending rows of refractory lining members 25 for said blocks to define a relatively narrow combustion space for the combustible mixture issuing from a multi-apertured inlet

2

28 in the flat wall member 24 in line with said space and defined by a longitudinally extending supply tube 21 at the back side of said wall member 24. The right hand lining members 25 are indicated by 26 and the left-hand members by 27. In Fig. 2 the said combustion space is shown as comprising a restricted passage 29 between primary and secondary combustion zones 30 and 31 but, as shown in Fig. 7, the said space may be of uniform width from top to bottom as indicated by 32. Generally speaking, it is the kind of gas to be burned that determines the preferred shape of the combustion space. Thus, for relatively slow-burning gases like natural gas, propane, butane, etc., a relatively restricted passage 29 between the two relatively wider combustion zones is found to be advantageous in promoting rapid combustion whereas in the case of manufactured gas like ordinary city gas there is no particular advantage in providing any such restricted passage.

The paired lining members 25 are held in place in the channel between the two rows of backing blocks 13 by providing on the block-facing side of the lining members a longitudinally extending lateral projection 45 and by providing in the channel side of the backing blocks a set-back 46 corresponding in shape to the said lateral projection 45 whereby to provide between said sides a pair of complementary abutments 47 and 48 tending to hold the lining members in place in said channel while at the same time permitting them to have longitudinal sliding movement relative to said backing blocks.

In order to maintain the two rows of lining members 25 in spaced relation, there is provided between the rows a series of spacer elements 35, said elements being positioned at the joints between adjacent ends of the lining members and being held in place by extending part way into the side of each row in a lateral pocket resulting from side notches 36 in the adjacent corner edges of said ends as will be readily understood by reference to Fig. 1. The spacer elements are of more or less stream-line form and, by reason of terminating far short of the outlet side of the combustion space, the longitudinal continuity of the issuing flame is not objectionally interrupted by said elements.

At each of its longitudinal ends, the combustion space is closed by refractory slab 37 which in turn is backed by a heating insulating slab 38. A cross bar 39 carried by the support 16 serves as a retaining barrier behind the outer slab 38.

At its ends, the fuel supply tube 21 is preferably closed by a removable head member 33 so as to

permit ready access to interior of the tube for removing dirt which may tend to clog the orifice of the gas outlet 28. Combustible mixture is supplied to said tube by a conduit means 34 leading from a suitable source of supply.

As best shown in Fig. 5, the longitudinal gas outlet 28 of the tube 21 will ordinarily consist of a multiplicity of relatively small-diameter drilled holes 40 whereby to minimize the likelihood of flame flashback into the tube. This likelihood is further minimized by reason of the tube being kept cool by the cooling water in the right and left-hand water passages 23 defined by walls 22 coacting with the back side of the flat wall member 24. The holes 40 are preferably arranged according to the pattern shown in Fig. 5 which is to say they are arranged in two laterally spaced groups of two rows each so that the fuel issuing from one longitudinal group of holes will tend to flow in scrubbing contact with or in relatively close proximity to the next adjacent wall or face of the combustion space between the refractory members 25 and so that the fuel issuing from the other group of holes will tend to flow in scrubbing contact with or in relatively close proximity to the other wall or face of said space, this arrangement tending to produce a turbulence which tends to accelerate combustion.

From what has already been said in connection with Fig. 8, it will be understood that it is merely for descriptive purposes that in the other views the burner has been shown and described as firing downwardly.

What is claimed as new is:

1. In a burner for producing a line of flame, in combination, an elongate support having a flat wall, two laterally spaced rows of backing blocks arranged along said flat wall to define between said rows an elongate channel, two laterally spaced rows of refractory lining members arranged in said channel with their backs in movable contact with said blocks to define in said channel a relatively narrow combustion space, means including a passage disposed along the back side of said flat wall and communicating through said wall for supplying combustible mixture to said combustion space, means individual to said blocks for securing the latter to the elongate support,

and means comprising stepped portions along contacting sides of the lining member and their backing blocks for retaining said lining members in said channel in longitudinal sliding relation relative to said blocks.

2. In a burner for producing a line of flame, in combination, an elongate support having a flat wall, two laterally spaced rows of backing blocks arranged along said flat wall to define between said rows an elongate channel, two laterally spaced rows of refractory lining members arranged in said channel to define between said members a relatively narrow combustion space, means including a passage disposed along the back side of said flat wall and communicating through said flat wall for supplying combustible mixture to said combustion space, means comprising a longitudinally extending set-back in that portion of the inner face of each backing block next adjacent said flat wall and a corresponding projection on the block-facing side of each lining member for holding the latter in place in said channel, and means for maintaining the rows of said lining members in laterally spaced relation comprising a series of insert elements which bridge the gap between opposite lining members at the joints formed by the longitudinally aligned lining members and whose terminals extend a substantial distance into said joint for support in a pocket formed by similar lateral notches in the end portion of said lining members.

ERNEST G. DE CORIOLIS.
